Attorney

UNITED STATES PATENT OFFICE.

HEINRICH ORTGIES, OF ERFURT, GERMANY.

SELF-LOADING PISTOL.

1,399,224.

Specification of Letters Patent.

Patented Dec. 6, 1921.

Application filed April 1, 1919. Serial No. 286,815.

To all whom it may concern:

Be it known that I, HEINRICH ORTGIES, manufacturer, citizen of the German Republic, residing at No. 30 Cyriakstrasse, in the 5 city of Erfurt, Germany, have invented certain new and useful Improvements in Self-Loading Pistols, of which the following is a specification.

The present invention relates to an arrangement for fixing the covers to the handle of pistols, and in particular of automatic pistols with which the magazine is disposed in the said handle. With the said arrangement the covers are secured in a reliable manner without the need of screws or studs, and they may be readily removed or be refitted after the magazine has been removed, without, however, there being a danger of the covers dropping off accidentally.

20 In the accompanying drawing the invention is illustrated as applied to an automatic pistol.

Figure 1 is a longitudinal section through the pistol. Fig. 2 is a rear view of the same, 25 the rear wall of the handle having been removed. Fig. 3 is a cross section on the line A—B in Fig. 1 and Fig. 4 is a detail view of the means for securing the covers. Fig. 5 is an inside view of a cover.

30 The rear wall 2 of the cavity 3 within the handle or butt 1 of the pistol intended to receive the magazine 4 is cut out in a certain manner to allow of fitting a bolt 5, which serves to hold the two covers 12 lying 35 on the two sides of the handle 1. This bolt 5 is formed in the embodiment shown by a lever pivoted at its lower end on a horizontal pin 6; the upper end of this lever has two laterally projecting ribs 7 formed at its 40 side edges which extend for a certain distance through the wall of the cavity 3 into the latter.

The bolt 5 is forced inwardly by means of a spring 8 bearing against the said bolt 45 and the rear wall of the handle, or, as in the embodiment shown, against the upper end of the lever 9 which is pivoted centrally on a pin 10, the lower part of which lever 11 forms the magazine holder. With this embodiment the spring thus fulfils a double 50 purpose, by simultaneously acting on the

magazine holder and on the bolt for the covers.

Each of the covers 12 (Figs. 3 and 5) which are removed in Fig. 1, is provided 55 on its inner surface with a projection 13, the front edge 14 of which is beveled or dovetailed and bears against a corresponding edge of the handle. On the rear edge of this projection is a recess 15 into which engages the respective rib 7 of the bolt 6.

From the description of the embodiment shown it is evident that the two covers are secured in a perfect manner, when the ribs 7 of the bolt engage in the recesses 15, and 65 are held in such engagement by means of the springs 8. When the magazine 4 is in position, the bolt 5 is inaccessible. For removing the covers it is therefore necessary to first remove the magazine from the handle, whereupon a backward pressure is exerted by aid of a rod or some other tool on the bolt, so that the spring is compressed and the locking ribs are disengaged from the recesses of the projections inside the covers. 75 The covers are fitted in a similar manner, after the bolt has been previously forced back.

The lever 5 may also be replaced by a bolt, which is disposed to slide in the handle. 80

The removing of the covers will not impair the operation of the pistol, which will always be possible, as long as the magazine is in position.

What I claim to secure by Letters Patent 85 in the United States is:—

1. In a firearm, a frame including a hollow handle; a pair of side covers removably engaged with the handle, each cover having an internal recess formed in it; and a locking bolt pivoted within the handle and having projecting portions engageable in said recesses.

2. In a firearm, a frame including a hollow handle; a pair of side covers removably engaged with the handle, each cover having a projection formed on its inner face, one portion of which is recessed; and a locking bolt pivoted within the handle and having projecting portions engageable in said recesses. 95

3. In a firearm, a frame including a hollow handle; a pair of side covers removably en-

gaged with the handle, each cover having an internal projection, the rear edge of which is provided with a recess; and a locking bolt pivoted within the handle and having spaced, 5 projecting ribs for engagement in said recesses.

4. In a firearm, a frame including a hollow handle; a pair of side covers removably

engaged with the handle, each cover having a recessed inner face; and a spring-pressed locking bolt pivotally mounted at its lower end within the handle and provided at its free upper end with projecting portions engageable in said recesses. 10

In testimony whereof I affix my signature. 15

HEINRICH ORTGIES.
